UNITED STATES PATENT OFFICE.

GEORGE ERNEST WICKENS, OF AVON, SOUTH DAKOTA.

ROAD DRAG.

Continuation of application Serial No. 424,897, filed November 18, 1920. This application filed March 13, 1924. Serial No. 699,142.

To all whom it may concern:

Be it known that I, GEORGE E. WICKENS, a citizen of the United States, and a resident of Avon, in the county of Bonhomme and State of South Dakota, United States of America, have invented certain new and useful Improvements in Road Drags, of which the following is a specification.

This invention relates to road working machines or drags of that type of construction which employs a pair of forwardly divergent elongated scraper elements or blades connected together and adapted to be drawn on an uneven road surface to effect leveling of the road surface.

This application is a continuation of my application filed on or about November 18, 1920, Serial No. 424,897, allowed June 22, 1923.

20 An object of the invention is to obviate such relative movements of the scraper blades as would result in one of the blades being moved forward independently of or for a greater distance than the other scraper 25 blade, the invention providing a connection between the rear ends of the scraper blades for holding the respective blades against rolling or turning about their longitudinal axes and for simultaneous forward movement.

30 A further object of the invention is to provide a road drag of the class described in which the scraper blades can be adjusted to vary the effective width of the drag within a relatively wide range.

35 A still further object of the invention is to provide a novel draft arrangement which has connection with the scraper blades adjacent to the rearward ends of the latter and 40 is adapted to transmit a pulling force to the blades so that such blades will be drawn forward to the same extent and in a like manner without causing any appreciable strain on the connection between the rear 45 ends of the scraper blades and without disturbing the adjustment of the scraper blades in respect to each other.

50 A further object of the invention is to provide a road drag which is provided with an arrangement for adjustably supporting the scraper blades adjacent to their rearward ends on the surface which is traversed by the drag so that the depth to which the blades will cut may be varied, and the distribution of loose material for filling in

depressions in the road surface can be regulated.

I attain the foregoing and other objects which will become apparent as the description proceeds by providing scraper blades 60 which are substantially channel shaped in cross sectional contour and are arranged with the edges of the flanges facing downward, the blades being hingedly connected together adjacent to their rearward ends 65 and being connected both adjacent to their forward and rearward ends to a central draft member in combination with a vertically adjustable gauge or ground wheel for supporting the rearward end portions 70 of the scraper blades.

The invention is illustrated in the accompanying drawings, wherein—

Figure 1 is a plan view illustrating the preferred form of my improved road drag 75 or grader with draft means for advancing the same,

Figure 2 is a rear elevation,

Figure 3 is a side elevation,

Figure 4 is a detailed fragmentary vertical sectional view of the adjustment means for the gauge wheel,

Figure 5 is a fragmentary side view showing the manner of journalling the gauge 85 wheel,

Figure 6 is a fragmentary plan view showing a modified cross connection between the rear ends of the side members or blades,

Figure 7 is a fragmentary plan view of 90 a further modification and illustrating another form of draft connection,

Figure 8 is a partial plan view of another form of connection between the rear ends of the blades,

Figure 9 is a rear elevation of the structure shown in Figure 8, and

Figure 10 is a perspective view of a socketed bracket employed for holding a supporting rod of the gauge wheel supporting 100 structure.

Referring to the drawings in detail, in which like reference characters designate corresponding parts throughout the several views, and particularly to Figures 1 to 5 inclusive, the improved device is shown as embodying relatively long and slim side members or bars 11 consisting of beams to which shearing members or blades 12 are bolted or otherwise secured, said blades being pro- 110

duced from channel bars of steel or other suitable metal placed with the flanges 13 thereof disposed to engage the earth or ground surface and produce a cutting or 5 shearing action and to effectively scrape and remove portions of highest elevation when drawn along the same. These rigid side members or bars are disposed in forwardly divergent relation. At their rear ends, 10 which are disposed closely adjacent to each other, a connection, is provided, the same consisting of two rigid bars 14 disposed in crossed relation, the point of crossing thereof being located between the rear ends of 15 the main side members or bars 11, and each of the bars 14 having a pivotal connection adjacent to one of its ends with one of the side members 11 adjacent to the rear end of the latter, and having a pivotal connection 20 adjacent to its other end with the other side member 11 at a point located an appreciable distance in advance of the rear end of the latter, thus maintaining the side members one opposite the other and positively preventing them from moving into unsymmetrical angular relation which would interfere 25 with uniformity of scraping and grading action. In this manner, a road drag is produced which is composed practically of two rigid members joined together at their rear ends to extend forward and toward the two sides of the road so as to produce a uniform action at both sides of the middle line of the road, the connecting bars of the cross 30 connection operating as a hinge and allowing the forward or outer ends of the main side members to be drawn close together or widely separated to meet different road conditions.

40 The drag may be drawn by a chain, or other connection, illustrated as a chain 17, which may be adjusted in length and which is provided with rearwardly divergent connections 18 secured at their rear ends to the 45 inner or rear ends of the main side members or blades. This chain or connection may be attached at its forward end to the motive power or draft animals, a portion 19 of a tractor being shown with a hinged connection 20 and a ring or the like 21 detachably connected thereto. The branched connection serves to draw the drag from its approximate center and relieve the cross connection of the strain of maintaining the side members in their proper relative positions.

55 From the respective forward or outer ends of the two main side members, two side connections 22 are provided and pass inwardly and slightly forwardly to the aforesaid point of attachment of the draft member to the motive power, these side connections serving to hold the outer ends of the side blades or members thereof in position. By this means, the device is drawn from the 60 rear and center, thus allowing a relatively

close hitch between the tractor, or other draft means and the drag, which allows good control and permits short turns. The side connections 22 preferably comprise rigid outer portions or sections 23 which are 70 bolted or otherwise fastened at their outer ends to the outer ends of the side members as shown at 24, so as to move or pivot horizontally and are prevented from moving or swinging vertically with respect to the side members; while the inner portions or sections 25 are flexible, being of chain, cable or the like and are connected to the inner ends of the sections 23 and to the hitch or pull chain. The outer end portions or sections of the side connections are of sufficient 75 length to have a steadyng effect on the side members and to assist the rear cross connection in resisting their tendency to roll.

The device may be adjusted from two feet 80 in width to more than ten times that width, the single main draft connection serving to cause equal pull on the two side members to maintain them equally advanced. The rigid sections 23 may be as short or as long as desired. The width of the roadway which is to be covered is regulated by adjusting the length of the main draft connection or hitch, which passes between the rear end of the drag and the point of attachment to the 90 motive power. The drag is drawn entirely by the main draft connection, and when the drag is operating at its maximum width, the side connections 22 lead out practically at right angles from the forward end of said draft connection or chain, and the side connections, even without the aid of the rigid cross connection or platform, serve to hold the side members or blades from rolling forwardly, as a result of friction between the road surface and the lower edges of the channel shaped bars forming the side members.

A supporting device at the rear of the drag, comprises a wheeled lever 26 made up of two forwardly convergent bars 27 pivoted for limited vertical swinging movement at their rear ends to the side members near the rear ends of the latter, as by means of substantially vertical pivot pins carried 110 by the bars 11 and extending loosely through openings 51 in the bars 27, the openings 51 enlarging toward their upper ends as best seen in Fig. 3. The bars 27 are joined together at their forward ends as shown at 28, 115 in order to move together.

This lever is provided with a ground engaging member which may consist of a gauge wheel or wheels, or skid, and as shown, bearings or hangers 29 consisting of 120 U-bolts or the like carried by the bars 27 of the lever support the axle 30 of a ground or gauge wheel 31 which by its engagement with the ground serves to support or partially support the rear end of the drag 125 130

proper for the purposes heretofore set forth. The lever is swung downwardly to bring the wheel in contact with the ground, and slidably engages a vertical rod 32 which is secured or supported in any suitable manner in vertical position and which as shown, is provided with a series of spaced apertures 33 adapted to be engaged by a cross pin 34 carried in aligned apertures in the opposed bars 27. The vertical rod 32 may be supported upon a platform 35 on the side members, the lower end of the rod being engaged in a socket 36 of a casting 37 forming a bracket or base plate which is secured to the platform, which latter is adapted especially for use when draft animals are employed. An upright frame or guide 38 is arranged on the platform at the forward edge of the latter and held in position by inclined side braces 39, the rear ends of which are connected to the platform at the rear edge of the latter. This frame and braces are especially adapted for use when the device is drawn by draft animals. However, it may be employed to give added weight or it may be omitted entirely, especially when employing the draft means as shown.

In Figure 6, a modification of the device is shown, in which the structure is the same, with the exception of the cross connection, a single bar 40 connecting the rear ends of the side members 11, in lieu of the cross bars 14. This single rigid bar is pivotally attached at 40^a to the side members 11 to extend across the rear ends of the side members so as to allow said side members to hinge as previously described but to resist any tendency of the side members to roll over. In this plan or form of the invention, the branched hitch is depended upon primarily, to maintain the side members in their proper relative positions. In the form of the device shown in Figure 6, the vertical pivot pins 50 work in slots or elongated openings 52 in the side members 11 as well as being loosely received in the openings 51 in the bars 27.

In the form shown in Figure 7, a flexible connection or chain 41 is employed to connect the side members at their rear ends in lieu of a rigid connection or bar. In lieu of the branch chains 18 of the hitch, stiff or rigid connections may be provided as shown at 42, the same being in the form of a V and branching from the rear end of the chain 17 for connection with the rear ends of the side members. In addition, the sections 23 of the side connections may be relatively long to prevent the side members rolling over.

In the form of the invention shown in Figures 8 and 9, a single rigid bar 43 shaped like an inverted U, is used to form the cross connection. The depending portions or legs 44 thereof at the extremities or ends are set

down into sockets in castings or the like 45, secured upon the side members detachably, as indicated at 46. These U-shaped members may be arranged singly or in crossed relation as previously described, producing practically the same results in operation. The drag is adapted to cover a wide road and still let the blades operate with a shearing action which positively reduces high places and carries all loose material forward and inward to the center to fill all low places. Also, by making the side members with a crown or downward curve from the inner to the outer ends it is possible to produce a road surface with any sort of cross-section desired.

The use of the supporting wheel allows the side members to unload all loose material carried ahead of them before it reaches the center of the road where it would not be needed and where it would form a ridge. It may also be explained that the use of the novel cross connections between the side members permits of relatively wide range of adjustment of width of the drag and permits the use of relatively light and long side members so that the device is adapted to cover a relatively great width while keeping the sides at a shearing angle and without requiring more power than is usually required to draw ordinary drags of approximately half the width.

The side members may be of any suitable integral or built-up construction, and the blades may be of any suitable cross section so long as provision is made for producing the necessary scraping or cutting edge or edges. The construction illustrated and described in which a beam is bolted or otherwise secured to the top of the channel side member, serves the purpose of raising the operating platform relatively high from the ground and to give a relatively great elevation to the front surface of the side member. The side connections 22 may be entirely rigid or partly rigid and partly flexible, as shown. When the platform is omitted, the vertical bar 32 may be supported by the draft connections 17 and 18, the latter, or portions thereof, being made sufficiently rigid for this purpose.

Having now particularly described and ascertained the nature of the invention and in what manner the same is to be performed, I declare that what I claim is:

1. In a road drag, the combination with a pair of forwardly divergent rearwardly convergent side members; of crossed rigid connections each pivotally connected at its opposite ends to the respective side members at points adjacent to the rearward ends of the latter.

2. In a road drag or grader, a pair of oppositely disposed forwardly divergent channel-shaped members with the flanges thereof

disposed downwardly, a platform disposed across the rearward portions of said members, connections at the rear ends of said members, a gauge wheel in rear of the platform for adjusting the elevation of said members at the central portion thereof, and draft means connected to said members.

3. In a road drag or grader, a pair of oppositely disposed bladed channel-shaped side members with the flanges thereof disposed downwardly, said members being connected at their rear ends, a draft chain having a branch rear connection to said member near the inner ends of the latter and having side connections with the extremities at the forward ends of said side members, and a lever having a wheel for contact with the ground, said lever being mounted for limited vertical movement at the rear ends of said members, and means to hold said lever in an adjusted position.

4. In a road drag or grader, a pair of oppositely disposed bladed members, a connection across the rear ends of said members to hold the same in V-shaped relation, a draft chain extending centrally forwardly from the rear ends of said members, a lever pivoted for limited vertical movement at the rear ends of said members and provided with a ground engaging member to raise said members when the lever is lowered, and means for holding said lever in a vertically adjusted position.

5. In a road drag or grader, a pair of oppositely disposed bladed members, a connection across the rear ends of said members to hold the same in V-shaped relation, a draft chain extending centrally forwardly from the rear ends of said members, a lever pivoted for limited vertical movement at the rear ends of said members and provided with a ground engaging member to raise said members when the lever is lowered, a bar slidably engaged by said lever, and means co-operating between the bar and lever to hold the lever in a vertically adjusted position whereby to raise and lower the intermediate portions of the side members.

50 6. In a road drag, a pair of forwardly divergent longitudinal scraper elements, hori-

zontal means swingingly connecting the rearward ends of the scraper elements and holding said scraper elements in spaced horizontal alignment at their rearward ends, a longitudinal hitch element connected at its rearward end to the scraper elements at points adjacent to the rearward ends of the latter and extending forwardly in a plane midway between the scraper elements, and means connecting the forward ends of the scraper elements and the longitudinal hitch element for holding the scraper elements against spreading apart from a determined relation and for co-operating with said first named connecting means to hold said longitudinal scraper elements from turning about their longitudinal axes when a pull is exerted on said hitch element, said last means comprising rigid sections having the remote portions thereof horizontally and pivotally attached to the scraper elements and the remaining portions thereof inclined, and flexible sections connecting the adjacent ends of the inclined portions of the inner sections of the hitch elements.

7. In a road drag, a pair of forwardly divergent longitudinal scraper elements, a pair of intermediately crossed rigid bars one of which is pivoted at one end to one of said scraper elements at a point adjacent to the rearward end of the latter and at its other end to the other scraper element at a point more distant from the rearward end thereof than the point at which it is connected to the first scraper element is distant from the rearward end of the latter, the other of said bars being similarly connected to the scraper elements and reversely disposed in respect to the respective scraper elements, a hitch element connected at its rearward end with the scraper elements at points adjacent to the rearward ends of the latter and extending forwardly in equi-distant relation to the respective scraper elements, and means connecting the hitch element with the forward ends of the scraper elements for holding the latter against spreading apart from a determined relation.

GEORGE ERNEST WICKENS.
